UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,291,215.

Specification of Letters Patent.

Patented Jan. 14, 1919.

Application filed June 9, 1917. Serial No. 173,712.

To all whom it may concern:

Be it known that I, JESSE A. B. SMITH, a citizen of the United States, residing in Stamford, in the county of Fairfield and 5 State of Connecticut, have invented certain new and useful Improvements in Type-Writing Machines, of which the following is a specification.

This invention relates to an improvement 10 in typewriting machines, and more particularly to an attachment of the fan-fold type, but in which the work-sheets are on separate strips, and is an improvement on my application No. 165,055, filed April 28, 1917, and 15 patent to Lester A. Wernery and Jesse A. B. Smith, No. 1,132,055, dated March 16, 1915.

The present improvement is applied to 20 an attachment for typewriting machines whereby a number of copies of the same piece of work can be simultaneously written, and a large number of pieces of work produced successively by the interleaving of carbon sheets with continuous strips or webs 25 of work-sheets. The carbon sheets are repeatedly used and the work-sheet strips spaced relatively to them for each new piece of work.

To effect the spacing between the work- 30 sheet strips and the carbon sheets, the platen is swung up out of its normal typewriting position so as to straighten out the bend in the pack of interleaved carbon and work-sheets. In this way, the friction is reduced 35 so that the work-sheet can be shifted relatively to the carbon sheets, and vice versa.

Where the work-sheet strips are separate, as in the present invention, there is a tendency of the sheets to creep relatively to one 40 another, due to the folding and unfolding around the platen. Provision is therefore made in the present invention for enabling the sheets, when they are spaced for each new piece of typewritten work, to be justified or re-registered relatively to one another, thereby preventing the creeping from being cumulative.

For this purpose, there are provided two or more studs which coöperate with perforations provided in the side margins of the work-sheets. These perforations may be used for assembling the completed sheets later in loose-leaf books, if desired. The studs are normally retired or moved to a

non-projecting position, so that when the 55 sheets are fed around the platen for typewriting the studs will not interfere with the line-feed movements of the paper. When, however, the platen is raised to a position to take out the bend or warp in the pack of assembled sheets, then the studs are automatically projected to gaging positions, so that the work-sheets can be strung thereon. Then, when the platen is returned to its normal position, the studs are automatically re- 65 ceded to a non-obstructing position, the sheets being then under the control of the usual feed rolls. The automatic projection and recession of the collating or gaging studs are preferably controlled by the swinging 70 of the platen from a normal typewriting position to a collating position and back again.

Other features and advantages will hereinafter appear.

Referring to the drawings,

Figure 1 is a perspective view, partly broken away, to show the underlying structure, and illustrating the platen in its normal typewriting position, with the pack of assembled work and carbon sheets wrapped 80 around the same, as shown in dash-and-dot lines.

Fig. 2 is a side view in elevation, with parts broken away to show the underlying structure, and the platen in the same position as in Fig. 1, in which position the studs are receded to a non-obstructing position.

Fig. 3 is a view in side elevation, similar to Fig. 2, except that the platen and the registering table have been swung to such a 90 position that the bend or bight in the pack of assembled work and carbon sheets has been taken out and the work and carbon sheets withdrawn rearwardly from the platen, enabling the forward spacing of the work-sheets relatively to the carbon sheets. The gaging or registering studs are shown in their projecting positions, which are coincident with the elevated position of the platen.

Referring more particularly to the separate parts of the device, 1 indicates the platen, which is secured to a platen axle 2, mounted on an auxiliary frame 3, within the usual platen frame 4. The auxiliary frame 3 has a pivotal mounting by means 105 of a rod 5 on the platen frame 4, so that it can be swung from the position of Figs. 1 and 2 to the position of Fig. 3. This is for

the purpose of relative re-adjustment of the work-sheets and carbon sheets in a manner more fully described hereinafter.

The usual lever 6 is provided for effecting line-by-line feeding movements of the platen 1. The line-space lever 6 is provided with an arm 7, which engages the usual slide 8, having an adjustable line-space dog, (not shown), which engages at the proper time a ratchet wheel 9, secured to an axle 10, carrying the usual knob 11, whereby the platen is ordinarily spaced back or forth several lines at a time.

In order to allow for the movement between the axle 10 and the axle 2, which are in alignment with each other, but separate, a special gearing is provided in said patent. There is secured on the axle 10 a gear 12, which takes all the movements of the axle 10, due to the line-space lever 6 and the knob 11. The gear 12 meshes with a broad pinion 13, which also overlaps a gear 14 of the same diameter as the gear 12, but secured to the axle 2. In this way, the movements of the line-space lever 6 and the knob 11 are transmitted to the platen 1. The pinion 13 is concentric with the rod 5, about which the platen swings as a center, so that there is no break in the driving train when the platen is moved between typewriting and re-registering positions.

To swing the platen 1, there is provided a hand-crank 16, secured to the swinging frame 3. The swinging frame and the hand-crank 16 are normally held in a typewriting position of the platen, by a latch 17, which engages a pin 18, provided on the hand-crank 16.

The work-sheets, which, in the present invention, are preferably in separate strips, coming from separate rolls or from a loose pack, (not shown), extend from a point somewhat in the rear of the platen. The work-sheets, indicated by the reference numeral 19, extend over a guide frame 20, which is secured to the platen frame 4, so as to travel with the carriage in a letter-spacing direction. This frame 20 is supported at its rear end by a roller 21, riding on a rail 22, carried by a pair of brackets 23, mounted on the frame of the typewriting machine or other suitable support.

The carbon sheets, indicated at 24, of which there are two shown, are supported so as to be interleaved between the work-sheets 19. For this purpose, there is provided a traveling table 25, having a movement toward the platen to keep pace with the advance of the sheets around the platen. The table 25 is provided with rollers or wheels 26, which travel in tracks 27, provided by the side rails of the frame 20. Extending alternately, inwardly from the frame 20 from the sides of the traveling table 25, are supporting arms 28 and 29 for

the carbon sheets 24. The inner ends of these arms are free, so that the looped ends of the carbon sheets 24 may be slipped onto the arms 28 and 29. If more work-sheets than three are used, more carbons may be provided, the sides of the traveling table 25 being provided with notches 30, into which extra arms may be secured.

The assembled pack of work-sheets, interleaved with carbon sheets, passes over a guide-rod 31, down between a paper-apron 32 and the platen 1. The usual pressure feed rolls 33 and 34 are provided for gripping the assembled pack of work and carbon sheets to the platen. From the pressure feed rolls 34, the pack of work-sheets passes up over the front of the platen 1, by the printing point, indicated at 35, Fig. 1, where the usual type-bars 36 strike the platen. From this point, the assembled work and carbon sheets pass up onto a registering table or board 37, which serves also as a guide. The registering table may be provided at its right-hand side with a slideable side gage 38, which may be adjusted lengthwise of the registering table for work-sheets of different widths.

At the left-hand side of the registering table 37, there are provided two or more openings 39, corresponding to perforations 40, provided in the work-sheet strips 19. These perforations may be used for assembling the separated pieces of work later in loose-leaf books, if desired. They are also used for adjusting the several strips relatively to each other from time to time, so that the alignment of the different sheets with each other may be accurate. This is necessary in cases where the work-sheet strips 19 each are composed of continuous repetitions of forms of some sort or other, and it is desired that certain portions of each form align properly with each other, so that matter may be typed in the proper place. The registering table 37 is extended at 41 to allow for one of the openings 39 and other mechanism to be now described.

The openings 39 in the registering table 37 are for the purpose of permitting studs 43 to be shifted from a normal, reeded position, shown in Figs. 1 and 2, to a projected position, shown in Fig. 3. The studs 43 are mounted on a block 44, which, at Fig. 2, is located in back of the registering table 37; and the latter being seen at this figure in its normal position. The block 44 is shifted by a slide 45. The slide 45 has pin-and-slot connections 46, with supporting lugs provided on the back of the registering table 37. A spring 47 tends to draw the slide 45 from the Fig. 2 position to the Fig. 3 position. This tendency is opposed by a rod 48, engaging a cam 49, provided on the slide. The rod 48 is secured to the fixed portion of the platen frame 4. When

the platen is in its normal typewriting position, the latch 17 holds it in this position, with the cam 49 locked by the rod 48. When the latch 17 is released and the hand-crank 16 swung forward to raise the platen 1, then the spring 47 acts as the cam 49 moves up from the rod 48, and draws the slide toward the platen and to the Fig. 3 position.

10 The manner of connection of the block 44 to the slide 45 is such that the longitudinal movement of the slide will produce a movement of the block 44 and the studs 43 at right angles to the movement of the slide. For this purpose, the slide is provided with inclined camming slots 50, into which project pins 51, provided on the block 44. Thus, when the spring 47 acts to draw the slide downwardly, the studs 43 will be projected through the openings 39, as in Fig. 3.

15 A leading edge gage 52 may be adjustably mounted on a bar 53, extending upwardly from the registering table 37, although when the studs 43 are used, it is not absolutely necessary to use the leading edge gage, except for convenience in tearing off the sheets, or unless a sheet of a magnitude including several of the perforations 40 is used.

20 A knife 54 may be provided for cutting off the sheets, as completed, from the main portions of the strips. This knife 54 is swingingly mounted on the rod 5, and may be manipulated between operative and inoperative positions by a hand-lever or finger-piece 55.

25 If it be assumed that the assembled pack of interleaved work and carbon sheets is at the printing point 35, ready to start a new piece of work, then the platen 1 will be in the position of Figs. 1 and 2, and the subject-matter can be written line by line. The work strips will be drawn on from the source of supply, and the traveling table 25 will advance with this movement as the carbon sheets travel with the work-sheets around the platen.

30 When the piece of work is completed, the pack of assembled work-sheets can be advanced, if not already there, to such a position that the perforations 40 are about in register with the openings 39. As the studs 43 are receded at this time, this may be approximately determined by the gage 52 adjusted to the proper point. The hand-crank 16 is then released, and the registering table 37 swung forward thereby, the sheets being released from the feed rolls 33, 34, and the operative gripping the sheets to the registering table. When the registering table and platen assume the position of Fig. 3, the studs 43 will be automatically projected by the operation of the spring 47, through the openings 39 and the

35 perforations 40, thereby re-registering the work-sheets accurately with reference to one another. It will be noted, by reference to Fig. 1, that the left margin of the work-sheet strips projects beyond the carbon sheets 24, so as to permit the passage of the studs without interference from the carbon sheets.

40 In this position of the parts, the kink or bend in the assembled pack of work and carbon sheets is taken out, so that there will be very little friction between the carbon sheets and the work-sheets. The traveling table 25 may then be forced rearwardly, so that the carbon sheets are withdrawn relatively to the work-sheets, to somewhat the position of Fig. 3, the work-sheets being held in the meantime by the studs 43 in their correct positions with reference to one another.

45 The platen and the registering table 37 may then be returned to their normal typewriting position, and locked in such position by the latch 17. During the final portion of this return stroke, the re-registering pins 43 are withdrawn and the sheets are again gripped by the feed rolls 33, 34, so that the alignment of the sheets relatively to one another is preserved. The completed piece of work may then be cut off by the 50 knife 54, and the platen rotated, either by the line-space lever 6 or by the hand-knob 11, to bring the initial blank line of the new sections of the strips or webs to the printing point 35. The new piece of work can then be typewritten, and the operation repeated 55 as before. Since the return of the platen and registering table automatically recedes the studs 43 to a non-obstructing position, they will not interfere with the oncoming leading edge of the newly registered sheets.

60 Variations may be resorted to within the scope of the invention, and portions of the improvements may be used without others.

65 Having thus described my invention, I claim:

1. The combination with a platen, arranged to support a pack of work-sheets and carbon sheets wrapped around the same, of means for taking out the kink or bend in the pack of work-sheets and carbon sheets, so as to decrease the friction therebetween, and normally receded projections, automatically brought by said means, to hold the work-sheets at a point in advance of the bight 115 of the platen, so as to permit the withdrawal of the carbon sheets relatively to the platen and the work-sheets.

2. The combination with a platen, arranged to support a pack of work-sheets and carbon sheets wrapped around the platen to form a bight or bend therein, said work-sheets having marginal perforations 120 therein, of studs for engaging said perforations to hold said work-sheets against move- 130

ment means for taking out the kink or bend in the pack of work and carbon sheets, so as to minimize the friction therebetween, and shifting means for said studs, moving them 5 into and out of play, operated by said first-mentioned means.

3. The combination with a platen, arranged to support a pack of work-sheets and carbon sheets wrapped around the platen 10 to form a bight or bend, of shifting means for the platen, arranged to take out the bight or bend, by straightening out the pack of work and carbon sheets, normally retracted impaling studs for said work-sheets, means 15 for bringing said studs into play when said shifting means moves said platen to a position to straighten out the bend in the pack of work-sheets and carbon sheets, and means to withdraw said carbon sheets relatively to said work-sheets.

4. The combination with a platen, arranged to support assembled work and carbon sheets, of means to displace said platen, one or more studs for assisting in registering said sheets, a spring normally tending 20 to project said studs to an active position, and camming means, acting against the tension of said spring, to retire said studs to an inactive position, said camming means operatively connected to said platen-displacing means.

5. The combination with a platen, arranged to support and manipulate interleaved carbon and work-sheets, of one or 35 more studs to cooperate in assembling or collating said sheets, spring means normally tending to bring said studs into active position, a registering table for assisting in assembling said sheets, said registering table 40 being shiftable between active and inactive positions, and camming means, operated by the movement of said registering table to a non-registering position, to oppose the action of said spring and retire said studs 45 to an inactive position, said camming means comprising two elements, one a rod and the other a cam, cooperating when the registering table is moved to a non-registering position, one of said elements being fixed and 50 the other being mounted to move with said registering table.

6. The combination with a platen, arranged to support and manipulate an assembled pack of work sheets and carbon 55 sheets, said sheets being wrapped around said platen, to form a bight or bend, of a registering table for assisting in properly interleaving the successive portions of the work-sheets with the same portions of the 60 carbon sheets, means for shifting said platen and said registering table in unison to bring the table to a registering position, and to straighten out the bight or bend in the work-sheets, thereby decreasing the friction be- 65 tween said work-sheets and said carbon

sheets, said work-sheets projecting at their side margins beyond the side edges of said carbon sheets, and being provided with perforations in their projecting portions, studs carried by said registering table, means for normally holding said studs in retirement when typewriting, and means, operated during the shifting movement of said platen and said registering table to a registering position, to project said studs into the perforations in said work-sheets, so as to hold them relatively to said carbon sheets, and means for retracting said carbon sheets relatively to said work-sheets, so as to clear a completed piece of work from said carbon 80 sheets, and reassemble the carbon sheets with new portions of the work-sheets.

7. The combination with a platen, shiftable from a normal typewriting position to a registering position, of studs for assisting in registering several sheets, a spring tending to project said studs to an effective position, and a latch for holding said studs in a retracted position, and maintaining said platen in a normal typewriting position. 85

8. The combination with a platen, of a registering table for said platen, normally ineffective studs cooperating with said registering table and arranged to engage in perforations in a plurality of sheets to be registered, said table being reversible from an upright position to an inverted, registering position, and a gage for determining the proper position of the sheets when the table is in an upright position and the studs are 95 ineffective, so that when the table is inverted and the studs become effective, they will project properly into the perforations in said sheets.

9. The combination with a platen, of a 100 registering table for said platen, normally extending above said platen when typewriting, and invertible to an upside-down position for registering, and studs normally retracted to a non-obstructing position, automatically projecting with the inversion of said registering table to engage perforations in the sheets to be registered, so that the sheets may be registered by the sense of touch. 105

10. The combination with a revoluble platen, of means for displacing said platen upwardly to straighten out the sheets, means to retract interleaved carbon sheets, a work-table upon the delivery side of the platen, 110 a re-registering pin at said table, said pin normally retracted, and means connected with the platen-displacing means for projecting said pin.

11. The combination with a revoluble 115 platen, of a feed roll to run upon the under side thereof, means for displacing said platen upwardly to release the work from said feed roll and straighten out the sheets, means to retract interleaved carbon sheets, a 120

work-table upon the delivery side of the platen, a re-registering pin at said table, said pin normally retracted, and means connected with the platen displacing means for projecting said pin during the upward movement of the platen, and for retracting said pin at the concluding part of the return stroke of the platen.

12. The combination with a revoluble platen, of means for displacing said platen upwardly to straighten out the sheets, means to retract interleaved carbon sheets, a work-

table upon the delivery side of the platen, a plurality of re-registering pins at the side of said table, said pins normally retracted, 15 and means connected with the platen-displacing means for projecting said pins during the upward movement of the platen, and for retracting said pins during the return stroke of the platen.
